UNITED STATES PATENT OFFICE.

HUGH HOUSTON, OF LAWRENCE, MASSACHUSETTS.

SEWING-MACHINE.

1,103,587.

Specification of Letters Patent. Patented July 14, 1914.

Application filed June 2, 1911. Serial No. 630,801.

To all whom it may concern:

Be it known that I, HUGH HOUSTON, a citizen of the United States, residing at Lawrence, in the county of Essex and State 5 of Massachusetts, have invented certain new and useful Improvements in Sewing-Machines, of which the following is a specification.

My invention relates to sewing machines 10 and while it is especially adapted for mill sewing machines suitable for sewing together the ends of rolls of cloth during the handling thereof in factories, the principle may be used in connection with any sewing 15 machine.

The principal advantage of my device is the facility with which long stitches can be made, more particularly as this can be done in connection with a continuous feed.

20 As is well known, there are several types of sewing machine actions between the feed and the operation of the needle. A well known sewing machine action has a needle with a vertical reciprocating motion in connection with a looper or other thread catching device for catching and holding the sewing thread. The most common feed principle comprises devices for advancing the cloth and also a device such as a presser 25 foot for holding it stationary while the needle enters and withdraws therefrom, such device being released when the needle leaves the cloth allowing it to then advance for the next puncture.

30 In the patent to Houston, No. 920,141, May 4, 1909, is shown a construction wherein the devices for holding the needle are sufficiently elastic to permit its operation in connection with a continuous feed device, 35 the needle traveling forward with the feed to a limited degree and being brought back to its original position by the elasticity of the holding parts after it has been withdrawn from the cloth. This construction 40 permits the use of a continuous feed but does not permit a very long stitch to be made. It does show elastic needle holding device and I prefer to use this construction in the present device.

45 My present device is of such character that in connection with a continuous feed of any type, a stitch of great length can be made without any undue stress on the parts. The principle involved is to subject the entire head to a sliding action corresponding

50 with the travel of the feed, in connection with needle operating mechanism which causes the needle to enter the cloth at the beginning of the slide motion of the head and to leave it as the slide motion terminates. 60 In this way, a stitch of almost any length can be obtained.

55 In the drawings, Figure 1 is a top view of the head and part of the feed devices. Fig. 2 is a front elevation of portions of the head and of the feed pulley. Fig. 3 is an elevation of a portion of the head and feed mechanism from the back or driving side of the machine the spokes of the removable pulley being shown as cut away and the hub being 70 shown in section as on line X-Y of Fig. 1. Fig. 4 shows from the back a modification of the feed construction, and Fig. 5 shows this modification from the side.

65 The construction of the head and needle operating mechanism may be any now used but I prefer to use the construction shown in the patent to Houston above mentioned wherein a long boss is used to hold the needle bar instead of a rigid construction 80 whereby with the elasticity of this boss and of the needle bar so suspended there is considerable give of the needle in its action with reference to the cloth.

75 A represents the column or post which supports the feed and driving mechanism as well as the head. This column is flat at the top 20 and is milled or planed smooth enough to present a smooth surface to and to permit the bottom of the base B of the 80 head, which is also milled or planed to a true surface, to slide thereon with a minimum of friction. This base B has slots 10 and 11 through which pass studs 12 and 13 into the top 20 of column A. A strip adjoining 85 and connecting slots 10 and 11 of top surface of base B is milled or planed to present a true surface at 14 on each side of slots 10 and 11. Studs 12 and 13 carry washers 15 and 16 which rest on the true surface 14 and 100 are held in place by nuts 17 and 18. By adjusting nuts 17 and 18, the base of the head can be kept in slideable relation with the top 20 of column A. Base B supports at one 105 end, a rear bracket 21 in which are suitable bearings for the needle driving shaft 22. Base B also supports the middle bracket 23 which has bearings for the other end of shaft 22. It also supports a front bracket 24 which preferably is extended to form the 110

needle posts 30 and 31 which carry gibbs between which is slidably mounted the needle slide 32. Needle driving shaft 22 carries and is driven by a removable pulley 50. 5 Needle slide 32 has a long elastic boss 33 which supports the needle bar 34 which carries the needle 35 as in the Houston patent described.

In alignment with needle driving shaft 10 22 and supported by bearings in front bracket 24 is the looper shaft 40 which carries at its front end a looper 41 in operative relation with needle 35, the same being a well known construction. I prefer 15 to cause needle slide 32 and the needle to be given a reciprocating action by means of a pitman 45 which is actuated by means of a pin, not shown, which connects disks 62 and 63 carried respectively by the rear 20 end of looper shaft 40 and the front end of needle driving shaft 22. From this construction it will be seen that as needle driving shaft 22 is operated by means of pulley 50, and as it transmits positively motion 25 to the needle and looper, the needle and looper coöperate. Preferably the needle operates through a slot 47 in a throat plate 48 and the looper is located underneath this plate.

30 For the feed, I may use a pulley C the edge of whose rim adjoins throat plate 48 and I preferably use such a pulley C provided with pins 60 which are projected through the rim thereof by means of a cam 35 or other contrivance while passing on each side of the needle and traveling with the top of pulley C and which are retracted when passing with the bottom thereof. Thereby the cloth to be sewed is carried forward 40 by the points of the pins while they project and is firmly held thereby until the needle has been passed. After passing the needle, the points of the pins are withdrawn permitting the cloth to drop. This pin pulley 45 construction is also well known being shown in patent to Ashton, December 10, 1907, No. 873,338. This feed pulley C is preferably driven by any suitable gearing, belts or other devices, not shown, from the 50 main driving pulley D of the machine. This main driving pulley D, by means preferably of a belt 51, drives removable pulley 50 and thereby needle driving shaft 22.

To cause the head slidably supported as 55 it is by base B to be given a reciprocating horizontal motion conforming in one direction to the travel of feed pulley C, I prefer to mount an eccentric 52 on needle driving shaft 22. The eccentric strap 53 of this 60 eccentric is carried by an eccentric rod 54 which is pivotally attached to an arm E which is fixed to a bracket attached to column A. The result of this connection is that as needle driving shaft 22 revolves, 65 it forces the whole head to slide horizon-

tally guided by bolts 12 and 13 as shown by the dotted lines in Figs. 1, 2 and 3. The length of this sliding is determined by the size and construction of eccentric 52. It is necessary or at any rate desirable that the parts should be so adjusted that the needle 35 should pass downward into the material as the head begins to move in the direction with the feed wheel C and that before the end of the slide of the head, 70 needle 35 should withdraw upward therefrom thereby avoiding any puckering of the cloth. I prefer a belt connection between pulleys 50 and D as that permits of pulley 50 moving with the head as shown in Figs. 75 1, 2 and 3. It is also a simple matter to change the size of pulley 50 and thereby to change the adjustment. The length of the slide of the head determines the length 80 of the stitch and this is adjusted by changing the size of the eccentric 52 and its strap 53. If the length of this stitch is to be decreased or increased, the speed of the needle with reference to the speed of the feed pulley should be changed to correspond 85 and this change is made by changing the size of pulley 50.

The type of feed is immaterial and while it is preferable that it should be driven 90 from the same source of power as the needle, it might be driven from a different source. All changes in the relation of the parts are made on the head.

In Fig. 4, I show a different form of feed wherein a straight throat plate 70 is 95 used in place of the curved throat plate 48 and preferably a presser foot 71 is used to hold the cloth down as it passes under needle 35. This feed comprises two rolls 72 and 73 which may be either fluted, or covered 100 with felt or other suitable material and which may be driven through a gear, shaft or pulley from any source of power, as for instance by connections from main pulley D. Either feed roll, as the lower roll, may 105 be driven positively and the other may be a friction roll or both may be positively driven. Feed roll 73 passes through a slot 110 not shown, in throat plate 70.

Feed pulley 73 should be pivoted to column A, and pulley 72, throat plate 70 and presser foot 71 must be supported by suitable standards and arms also attached to column A so that they will not move with the head.

I prefer the construction shown in Figs. 4 and 5 wherein feed pulley 72 is pivotally carried by an arm 75 pivoted to a standard 76 and presser foot 71 is adjustably supported by arm 75. Throat plate 70 is fixed 115 to another arm 77 attached to standard 76. A spring 78 between arms 75 and 77 holds pulley 72 and presser foot 71 yieldingly 120 against feed pulley 73 whereby the cloth being sewed is held frictionally in place. 125

What I claim as my invention and desire to cover by Letters Patent, is:

1. In a sewing machine having a post and a bracket attached thereto, the combination with continuous feed devices supported by the post, of a head slidable on said post in a direction parallel with the feed and having a looper and a needle in operative relation with each other and proximate the feed devices and having a needle driving shaft and an eccentric carried by the needle driving shaft and an eccentric strap carried by said eccentric and pivotally connected by an eccentric rod to said bracket as described.
2. In a sewing machine, the combination with continuous feed devices, of a head having a reciprocating needle and a thread catching device both in operative relation with each other and proximate the feed devices, said head being provided with means whereby it is positively caused to move in one direction parallel with the feed and back to its original position, together with driving means for the head mechanism movable with the head.
3. In a sewing machine, the combination with a feed pulley provided with pins which are projected through the rim and retracted therefrom as the pulley rotates, of a head having a reciprocating needle and a looper in operative relation with each other and proximate the feed pulley, said head being

slidable back and forth in a direction parallel with the movement of the feed pulley, and means whereby the head is positively caused to move in one direction with a portion of the feed pulley and back to its original position, together with driving means for the head mechanism movable with the head.

4. In a sewing machine, the combination with a feed pulley provided with pins which are projected through the rim and are retracted therefrom at certain portions of the rotation as the pulley rotates, of a head slidable back and forth in a direction parallel with the movement of the feed pulley, means whereby the head is positively caused to slide back and forth in a direction parallel with the movement of a portion of the feed pulley, and driving means for the head mechanism movable with the head, together with a reciprocating needle and a looper in operative relation with each other and proximate the feed pulley, said needle being supported by the needle bar and a long boss whereby it is in elastic relation with the feed mechanism.

In testimony whereof I hereto affix my signature in presence of two witnesses.

HUGH HOUSTON.
